COLLAPSIBLE TUBE FINISHING MACHINE

John H. Fridén, Maplewood, N. J., assignor to
The Sun Tube Corporation, Hillside, N. J., a
Corporation of New Jersey

Application December 31, 1934, Serial No. 759,910

71 Claims. (CL. 29—38)

This invention relates to automatic machines for performing a series of operations upon a given object or continuous series of objects, and more particularly to a machine for performing a series of operations in the manufacture of collapsible metal tubes, such as are commonly used to contain pastes, creams, ointments and the like.

An object of the present invention is the provision of automatic means for performing a plurality of correlated operations, as will be fully explained hereinafter, upon a continuously-supplied series of partly finished tubes of the nature mentioned, by which the tubes will be substantially completely finished when discharged from the machine. In this connection it is a feature of the invention to provide separate operating means and controls for different portions of the machine by virtue of which maximum efficiency in the operation of all parts is increased.

Other and separate objects are the provision of automatic and novel means for performing each of the operations hereinafter disclosed. Still further objects and advantages will appear from the description which follows, together with the accompanying drawings in which:

Fig. 1 is a front elevation of the machine, showing the coater and coater adjusting means in section.

Fig. 2 is an enlarged detail view in vertical section along the line 2—2 of Fig. 1, showing the cap raising and feeding mechanism in the cap feed hopper.

Fig. 3 is a rear elevation of the machine.

Fig. 4 is a side elevation as viewed from the right in Fig. 1.

Fig. 5 is a plan view of the machine, a part of the cap hopper being broken away to show some of the mechanism beneath it.

Figs. 6 and 7 are enlarged detail views, in plan and side elevation, respectively, showing mechanisms for introducing cork inserts into caps.

Fig. 8 is an enlarged detail view in section taken substantially on the line 8—8 of Fig. 3.

Fig. 9 is an enlarged vertical skeletonized section on the line 9—9 of Fig. 4, showing the turret and spindle driving means together with the means for varying the speed of operation of various portions of the machine.

Fig. 10 is a detail plan view, partly in section, of the mechanism employed for positioning the tubes on the spindles of the turret.

Fig. 11 is an enlarged detail view showing, in side elevation, the tube push-on finger and the raising and lowering mechanism therefor.

Fig. 12 is a plan view of a portion of the mechanism shown in Fig. 11.

Fig. 13 is a vertical section on the line 13—13 of Fig. 11, showing the mechanism of Fig. 12.

Fig. 14 is a vertical section along the line 14—14 of Fig. 11, showing certain drag producing means included in the mechanism for raising and lowering the push-on finger.

Fig. 15 is an enlarged front elevation of the tool unit head and associated mechanism.

Fig. 16 is a side elevation, partly in section, of the mechanism of Fig. 15 as viewed from the right.

Fig. 17 is a plan view, partly in section, of the mechanism shown in Fig. 15.

Fig. 18 is a detail view in horizontal section on the line 18—18 of Fig. 15.

Fig. 19 is a detail in vertical section on the line 19—19 of Fig. 18.

Fig. 20 is a vertical section on the line 20—20 of Fig. 16, showing a cam shaft and driving means therefor.

Fig. 21 is a vertical section on the line 21—21 of Fig. 15, showing the tube threading mechanism.

Fig. 22 is a vertical section on the line 22—22 of Fig. 15, showing the tube end-facing mechanism.

Fig. 23 is a vertical section on the line 23—23 of Fig. 22, showing the tool adjusting means of the end-facing mechanism.

Fig. 24 is a vertical section on the line 24—24 of Fig. 15, showing the burr removing mechanism.

Fig. 25 is a vertical section on the line 25—25 of Fig. 24, showing the adjusting means for the burr tool.

Fig. 26 is a detail view in side elevation, partly in section, as viewed from the left in Fig. 1, showing the independent drive mechanism for the coating roller.

Fig. 27 is an enlarged detail, in vertical section, on the line 27—27 of Fig. 3, showing the main driving means.

Fig. 28 is an enlarged detail, in front elevation, of the cork and cap applying mechanism of the machine.

Fig. 29 is a horizontal section on the line 29—29 of Fig. 28.

Fig. 30 is a vertical section on the line 30—30 of Fig. 28, showing a cap pushed into a cap chuck after insertion of a cork gasket.

Fig. 31 is a horizontal section on the line 31—31 of Fig. 28, showing the application of a cap to a tube.

Fig. 32 is an enlarged detail, in elevation, of

the end of the capping lever, showing the capping chuck.

Fig. 33 is an enlarged vertical section on the line 33—33 of Fig. 8, showing the capping chuck operating mechanism.

Fig. 34 is an enlarged detail, in vertical section, on the line 34—34 of Fig. 6, showing the mechanism for moving the capping chuck longitudinally of the machine.

10 Fig. 35 is an enlarged detail, in vertical section, on the line 35—35 of Fig. 5, showing the tube feeding means and metal scrap chute.

15 Fig. 36 is a detail, in vertical section, on the line 36—36 of Fig. 37, showing the spindle drive and pin operating mechanism.

Fig. 37 is a fragmentary rear elevation of one of nine spindle operating devices.

20 Fig. 38 is a side elevation of the parts shown in Fig. 37.

25 Fig. 39 is an enlarged perspective view of the front end of one of the spindle pins.

Fig. 40 is an enlarged detail plan view of the spindle pin cam operating mechanism.

25 Fig. 41 is a vertical section on the line 41—41 of Fig. 40.

Fig. 42 is an enlarged detail, in front elevation, of metal scrap removing mechanism of the machine.

30 Fig. 43 is a detail, in vertical section, on the line 43—43 of Fig. 44, showing certain friction drag means for the swinging arm which removes the metal scrap from the spindle.

Fig. 44 is a plan view of the parts shown in Fig. 42.

35 Fig. 45 is a horizontal section on the line 45—45 of Fig. 42, with the metal scrap removing parts shown in a shifted position, and

40 Fig. 46 is a diagrammatic view showing the sequence of operations performed and the relative positions of the stations at which such operations are conducted.

45 Before describing the machine illustrated in the drawings in detail it will be useful to consider the general nature of the machine of the present invention. In the manufacture of collapsible tubes it is usual to form the unfinished tubes by the extrusion process applied to slugs of suitable material, such as tin, aluminum, zinc, lead or the like. This results in the production of cylinders of the desired diameter, formed, usually, with a short closed neck, of lesser diameter, at one end, and open at the other end. The length of the cylinder varies somewhat, and the edge of the open end is somewhat irregular. The machine 50 of the present invention is intended to receive the extruded tube, as described, and to perform the necessary steps to substantially finish the tube and place it in condition to receive the material to be marketed in it. These steps include trimming the open end to provide a tube of predetermined length, cutting off a short length of the closed end to open the neck, threading the neck, removing the burr and bevelling the end of the neck, coating the tube, inserting a cork gasket in a cap, and screwing the cap onto the neck. The tube is then transferred to a conveyor which takes it to the oven in which the coating is baked on. In this form the tube is ready to be filled except for the printing of any desired design or matter on the surface of the coating, which must be performed by a separate machine.

55 In the particular embodiment illustrated in the drawings, the machine includes a head or turret fitted with nine spindles. The turret is intermittently revolved by a Geneva movement,

each step of movement being one-ninth of a revolution of 40° in extent. It is thus seen that there are nine "stations" at each of which some operation is performed. The sequence of operations will be best understood by reference to Fig. 46, in which the turret is represented diagrammatically, with each station identified according to the operation performed thereat. It will be observed that five of the nine stations into which each spindle is shifted in the course of rotation 10 of the head are devoted to the performance of the five operations specified.

60 Referring to the Fig. 46, the rough tubes are supplied from an extrusion press or other source by the conveyor 5, which deposits them in the serpentine chute 6 arranged to contain a sufficient number of tubes T to maintain the machine in operation during a brief period in the event of an interruption in the supply. The serpentine chute, furthermore, serves to present the tubes in proper alignment to the receiving spindle. A rotatable head or turret 7 is provided with nine spindles 8, the nature of which is best illustrated in Fig. 36. At station A the lowermost tube in the chute 6 is pushed onto a spindle 8 by the operation of 20 the push-on mechanism, illustrated in detail in Figs. 10-14, inclusive. At station B the spindle is revolved so that the tube may be trimmed, and the end of the neck cut off, by mechanism illustrated in Figs. 16, 20, 22, and 23. At station C the 30 neck is threaded by the mechanism of Fig. 21, while at station D the burr is removed by the devices of Figs. 17, 18, 24, and 25 and the end of the neck is bevelled, the spindle being revolved at both of these stations. At station E the spindle is revolved at a different rate, and the tube is coated, by the means shown in Figs. 1 and 26, with enamel or other coating substance. At station F the spindle is revolved, again at a different rate, for the application of the cap. Additional 40 devices (Figs. 2 and 28-34, inclusive) are arranged adjacent this station (see Fig. 1) for feeding the caps and supplying them with cork gaskets. At stations G and H the spindles are stationary, and the tube may be removed from the 45 spindle at either station and placed on a conveyor to be carried to the oven. The removing and transporting means are not a part of the present invention. At station K the scrap material remaining on the spindle from the trimming operation performed at station B is removed by the device illustrated in Figs. 42-45, inclusive. The spindle is then ready to receive another tube as the operation of the Geneva mechanism (Fig. 9) moves the spindle again to station A. Consideration 50 of the foregoing will facilitate an understanding of the details of the drawings and of the description which follows.

55 The general arrangement of the machine is best seen in Figs. 1, 3, 4, and 5. Referring to Fig. 1, the conveyor 5 is shown at the right, arranged to feed the extruded tubes T into the chute 6. The turret 7, carrying the spindle 8, is driven intermittently in a clock-wise direction, through the Geneva driving arm 9 (Figs. 1, 5, 65 and 9), operated by connections, to be explained, from the motor 10. The mechanism for pushing the tubes T from the lower end of chute 6 onto the spindles 8 is designated generally at 100, the trimming and end facing mechanisms at 200, 70 the threading mechanism at 300, and the burr removing and bevelling mechanism, or end finishing mechanism, at 400. The coating mechanism is designated generally by the reference numeral 500, and the corking and capping mech- 75

anisms by the numeral 600. The scrap removal mechanism is indicated by the reference numeral 800. For convenience the details of each of the various mechanisms will be hereinafter designated by numbers within the hundred group of the general designation above specified. A separate motor 12 is employed to drive the coating mechanism 500. The entire machine is supported upon a suitable frame 13.

10 Main driving mechanism

Fig. 9 is a skeletonized view of the various operating devices powered by the main motor 10. The capacity of the machine is, of course, governed by the speed of rotation of the turret 1, which is driven through belt 17, chain 18, and Geneva arm 9. In order to vary the speed of the turret, the motor shaft is provided with a reeve pulley 19, which is adjustable, in the well known manner, by means of an adjusting screw 20. The speed of the belt 17 is thus controlled, and through it, the speed of flat pulley 21 (see Fig. 27), chain 18, the Geneva arm 9 and the turret 1. Chain 18 transmits the drive from a sprocket 16, connected with pulley 21, to a sprocket 16a. The latter is connected with the Geneva driving arm through speed reducing gears 22 and 23, reversing gears 24 and 25, and a driver gear 26 which is connected with the Geneva arm through a shaft 138 to which they are both secured. Arm 9, in turn, drives a Geneva wheel 27. The nine driving slots of the latter are arranged 40° apart, to provide for nine equal movements resulting in one revolution of the turret 35 upon nine revolutions of arm 9. The Geneva wheel 27 is secured to the turret 1 by a series of screws 28 (see Fig. 8), and the combined revolving structure is mounted upon a hollow arbor 29. It will be understood that the Geneva arm 40 has associated with it a locking disc arranged to cooperate in the usual way with the scallops in the Geneva wheel to lock the latter between the successive partial rotations.

Revolution of the spindles 8, when positioned at stations B, C, and D, is caused by frictional engagement of pulleys 15 (Fig. 36), carried by the spindles, with a belt 30, which is supported upon a number of free guide pulleys 31, 32, 33, and 34, and a driven pulley 35. A belt 36, which drives pulley 35, through a pulley 35a secured to the same shaft, is driven by a reeve pulley 37, keyed to a shaft 38 upon which the flat pulley 21, heretofore mentioned, is likewise fixed, and which is driven by the motor 10 through the belt 17. The speed of the belt 36, and hence the spindles at stations B, C, and D, is controlled by a tension device (see also Fig. 3) comprising a pulley 39, rocker arm 40, and adjusting screw 41, cooperating with the belt and varying the radial position of the belt with reference to the reeve pulley 37 (Fig. 27). It will be understood that since belt 36 is driven from the pulley 21 the speed of this belt and also belt 30 will be governed not only by the tensioning device just explained, but by the general machine speed adjusting screw 20 as well.

Revolution of the spindles at station F is caused by frictional engagement of their pulleys 15 with a belt 42 which is supported upon free guide pulleys 43 and 44, and a driven pulley 45. The tension of the belt 42 is controlled by means of a tension screw 46. The pulley 45 is keyed to a countershaft 69, which also carries a pulley 70. A belt 71 drives pulley 70, being in turn driven by pulley 72 secured to shaft 38 (Fig. 27).

Spindle mechanism

Referring to Fig. 36, it will be seen that each spindle 8 comprises a shank 47, around a portion of which is mounted a bearing sleeve 14, keyed to, or otherwise constrained to rotate with, the shank 47. The pulley 15 is mounted on the sleeve 14. A series of cylindrical spindle adapters 48, for varying the size of the spindle in accordance with the size of the tubes to be worked on, are carried by the projecting end of the spindle, the adapters being locked in place by a spindle head 49 which is threaded into the forward end of the shank 47. A spindle pin 50, which extends longitudinally through the spindle from end to end, has its extreme forward end formed with a suitable burr 51 (Fig. 39) for gripping the interior surface of the neck of the tube T while on the spindle, to prevent relative rotation between the tube and spindle. Near its forward end the spindle pin is provided with one or more grooves 52, which cooperate with a lock screw 53 in preventing relative rotary movement between the spindle pin 50 and the remaining parts of the spindle, while a limited longitudinal movement of the spindle pin with relation to the shank is permitted, as will be explained.

Each spindle 8 is rotatably mounted in forward and rear turret plates 54 and 55 of turret 1, by means of the bearings 56 and 57, which may be constructed in any suitable manner. At the rearward end of the spindle is provided a cap 58, which is threaded onto the rear end of the spindle pin 50 and is keyed to the ball-bearing sleeve 14, as by a pin 59, so as to permit of longitudinal movement but no rotation with respect thereto. It will be seen, therefor, that the spindle pin 50 and the cap 58 may move back and forth, within the spindle, to a limited extent.

Normally the spindle pin 50 and cap 58 are maintained in a forward position by means of the pressure of a spring pressed lever 60 pivoted at 601 upon the rear turret plate 55. However, when the spindle leaves station F, where the cap has been applied to the tube, it is desirable to retract the spindle pin 50 to release its grip upon the neck of the tube, in order that the tube may be easily withdrawn from the spindle. This retraction is accomplished by means of a cam 61 and cam lever 62, which cooperate, at the proper time, in forcing rearwardly the cap 58 and with it the spindle pin 50. The cam 61, which is annular, is secured, by screws or otherwise, to a cover 63 for the bearing 57, which in turn is secured to the rear turret plate 55. The cam lever 62 which is substantially annular in form, is journaled upon the bearing cover 63, and is maintained in engagement with the cam 61 by means of the pressure of the spring pressed lever 60, transmitted through the spindle pin 50 and cap 58, an annular flange 64 of which overlaps the cam lever 62.

Suitably mounted on a projection of the cam lever 62 is a roller 65, which is adapted to cooperate with a cam 66 (Fig. 41) mounted upon a portion of the stationary frame of the machine at that point in the rotation of the turret at which it is desired to retract the spindle pin 50. Referring to Fig. 41, as the turret 1 is moved in the direction indicated by the arrow, after leaving station F, the roller 65 will come in contact with the cam 66 and will be retarded, thereby causing a counterclockwise movement of the cam lever 62 with respect to cam 61. Due to the face cam formations on the elements 61 and 62 this will

result in the latter being forced rearwardly, as shown in Fig. 40, against the pressure of the spring pressed lever 60, thus carrying with it the cap 58 and spindle pin 50. At the same time a spring 67 is being tensioned by the retardation of cam lever 62, to which one end is connected by an arm 68, while the opposite end is connected to a pin on the plate 55. The neck of the tube T is thus released from the burr 51 on the end of the spindle pin 50.

As best shown in Figs. 40 and 41 the cam 66 is preferably mounted adjustably on the frame. For this purpose it is secured to a slide 73 having an extension 74 providing a dovetailed connection 15 with a bracket 75. A thumb screw 76 may be turned to adjust the vertical position of the slide and cam 66. Bracket 75 may be adjustably carried by the frame through cooperation of bolts 77 with elongated slots 78 in the bracket. This 20 allows for suitable horizontal adjustment of the cam.

As the turret continues its movement the roller 65 travels along the inclined portion of cam 66, and finally reaches a point where the cam lever 25 62 is fully restored. The cam 66 may be so formed as to permit the lever 62 to move to its normal position, under compulsion of the spring 67 at any speed desired. If this action is permitted to take place quickly the spindle pin moves 30 suddenly forward and strikes a sharp blow against the neck of the tube on the spindle, and since the tube is no longer restrained by the pressure of any of the various tools which have been operating on it, it is loosened and moved slightly forward on the spindle, facilitating its manual removal therefrom. In the machine as illustrated the release of the cam lever 62 takes place as the spindle moves from station G to station H. The spindle is now, except for the removal of 35 scrap at station K, in condition to receive a fresh tube, which operation will be described in connection with the push-on mechanism.

Within the circle described by the spindles there is arranged a tool unit head 82 (Figs. 15 45 and 17) which, as will be later explained in greater detail, carries tools for trimming both ends of the tube, a tool for threading the neck and a tool for finishing the neck end of the tube. This tool unit head comprises a casting 83 (Figs. 8 and 17) 50 having a portion fitting telescopically within the drum or hollow arbor 29. A shoulder 84 on the casting abuts the end of the drum 29 and also extends along a portion of the front face of the turret to assist in retaining the latter in place. For the purpose of securing the casting 83 a bolt 55 85 is passed through a central aperture thereof and is provided with a nut 86 at its end cooperating with a boss on the casting. The bolt 85 passes completely through the drum 29 and has 60 its head fitted within a recess formed centrally of a casting 87. The latter has a portion fitting telescopically within the drum and a shoulder abutting the end of the drum and a portion of the frame 13. A hollow casting 88 suitably bolted 65 to the casting 87 serves to support certain gearing and shafts which will be later described.

For the purpose of preventing over-rotation of the turret 1 in its step-by-step movements a suitable frictional device is preferably employed. This consists of a ring 89 (Figs. 8 and 17) carried 70 by the turret and engaged by a friction ring 90 held against rotation. Ring 90 is secured to a ring 91 having a pair of guide pins 92 riveted thereto at diametrically opposite points. These 75 pins pass through openings in screw threaded

bushings 93 (Fig. 15) which are adjustably mounted in brackets 94 secured to the tool unit casting 83. Springs 95 compressed between the bushings 93 and the ring 91 yieldingly force the friction ring 90 against the ring 89. By proper adjustment of the bushings 93 the friction may be suitably varied.

Push-on mechanism

Referring first to Fig. 35, there is shown in detail the chute 6, which receives the extruded but unfinished tubes from the conveyor 5. The chute is of such form as to provide for the storage of a supply of tubes sufficient to maintain the machine in operation during a brief interruption in the supply of tubes by the conveyor. If an extended interruption is encountered the chute 6 may be fed temporarily by hand from another source. The form of the chute, furthermore, is such that correct alinement of the tubes is insured in their transit, and particularly as they reach the lower end of the chute. In order to permit proper presentation of the lowermost tube in the chute to the spindle which is to receive it at station A, provision is made for both vertical and horizontal adjustment. For this purpose the chute is adjustably carried by a bracket 79 which, in turn, is adjustably secured to the main frame 13. Vertical adjustment of bracket 79 on the frame 13 is effected by a thumb screw 20 80, while horizontal adjustment of the chute on bracket 79 is effected by a thumb screw 81.

The push-on mechanism, for transferring the extruded tubes from the chute 6 to the spindles, is indicated generally at 100, Fig. 1, and is illustrated in detail in Figs. 10-14, inclusive. Referring to Fig. 11, a hollow tube 101 is slidably mounted in a bearing 102. A push-on rod 103 is slidably mounted in a bearing 104, and is also capable of limited rotation, as hereinafter explained. The bearings 102 and 104 are bolted or otherwise secured to a portion of the machine frame. As best shown in Fig. 4, the tube 101 and rod 103 extend nearly the full depth of the machine from front to rear and are supported 40 at several points in addition to the bearings mentioned.

Connecting arms 105 and 106 (Figs. 4, 10, 13) have hub or sleeve portions surrounding the hollow tube 101 and push-on rod 103 and serve to connect these parts. The arms are secured in desired position on the tube 101 by means of set screws 107 and 108. The connecting arms 105 and 106 are not rigidly secured to the push-on rod 103, but slidably receive the latter, so as to 50 maintain parallelism between the push-on rod and the tube 101, while at the same time permitting independent sliding and rotary motion of the push-on rod. Relative movement between the rod 103 and arms 105 and 106 is limited in 55 one direction by collars 1050 and 1060 secured to the rod. A push-on finger 109 is mounted upon the push-on rod 103 at or near the forward end thereof, and is locked in place by a set screw 110.

A bell crank 111 is pivoted upon the connecting arm 105, as at 112, and is connected, as at 113, with a drag rod 114. The other extremity of the bell crank 111 is connected, as at 115, with a link 116, which in turn is connected to a rocker arm 117 (Fig. 12), carried by the push-on rod 103 and secured in definite relation thereto by means of a set screw 118. The oscillatory movements of the bell crank 111 are limited by the adjustable stops 119 and 120, mounted upon 65 70 75 80 85 90 95 100 105 110 115 120 125 130 135 140 145 150 155 160 165 170 175 180 suitable brackets extending from the connecting arm 105.

Mounted upon a bracket 125 secured to the machine frame adjacent the bearing 102, is a drag device 126 (Fig. 14) comprising any suitable means for imposing a suitable and adjustable friction drag upon the drag rod 114, which it engages. In the embodiment shown, friction elements 127 and 128 formed of leather are provided, one on either side of the rod 114, and may be adjusted by tightening or loosening screws 129 and 130.

In order to support and guide the hollow tube 101, a collar 121 is mounted on the tube and is provided with a key 122 (Fig. 13), the collar and key being attached to the tube 101 by screws as shown. Guide members 123 and 124 are mounted upon the frame of the machine, and define a keyway in which the key 122 is slidable longitudinally.

In the rearward end of the hollow tube 101 is secured, by any suitable means, a rod 131, on which is slidably mounted a hollow block 137 to which a push-on yoke 132 (Figs. 4 and 10) is connected by means of links 133 and pins 134. A coil spring 135 surrounds the rod 131 and is retained between the block 137 and a nut 136 secured to the rod. The effect of the spring 135 is to maintain the block 137 in abutment with the rear end of the hollow tube 101, except at the extremity of the rearward or push-on stroke of the yoke 132, as will be explained hereinafter. It will thus be seen that by the means described a yielding driving connection is effected between the yoke 132 and the tube 101 and its associated mechanism.

The push-on mechanism driving means is illustrated in Fig. 3, the power being supplied by the main driving motor 10. As already explained in connection with the main driving mechanism, the sprocket 16a carried by a shaft 138, is driven by the motor 10 through means hereinbefore described. Keyed upon the same shaft 138 with the gear 26, and rearwardly thereof, is a gear 139 (Figs. 3, 4), which meshes with gear 140, which in turn meshes with gear 141 secured to a stub shaft 142. Keyed upon the stub shaft 142 is a bevel gear 143, which meshes with upper and lower bevel gears 144 and 145, the arrangement of the bevel gears being best illustrated in Fig. 8. Bevel gear 145 is keyed to a partly hollow shaft 146 which is supported in a suitable bearing 147. Also keyed to shaft 146 is a crank disk 148, provided with a crank pin 149, which is adjustable radially by means of adjusting screw 150. The crank pin 149 engages a bearing aperture 151 in the yoke 132, and is secured by means of a nut 152. The aperture 151 is substantially central of the yoke 132, one end of which is connected to the hollow tube 101 by the means already described. The opposite end of yoke 132 is journaled upon a stud 153 which projects vertically from a bracket 154 suitably secured to the machine frame.

From the foregoing it is apparent that the yoke 132 is given an oscillatory movement in a horizontal plane, the period of oscillation being directly related to the speed of the other mechanism driven from the main motor 10, including the turret 1.

The operation of the push-on mechanism is as follows: When the yoke 132 is moved toward its forward position by means of the revolution of the crank disk 148, the hollow tube 101 is moved forwardly, carrying with it the connecting arm

105 and bell crank 111. Since the drag rod 114 is gripped frictionally by the drag device 126, the forward movement described results in a counter-clockwise rotation of the bell crank 111 until the latter engages the stop 120. The described movement of bell crank 111, through the link 116 and rocker arm 117, effects a short rotation of the push-on rod 103, to raise the push-on finger 109 to the position shown by broken lines in Fig. 13, but the rod does not move forward at this time. The continuing forward movement of the tube 101 then results in a corresponding forward movement of the push-on rod 103, until the push-on finger 109 has passed over the lowermost tube T in the chute 6 (see Fig. 1). At this point the rearward motion of the yoke 132 and associated mechanism commences, and the reverse of the above-described movements takes place. That is, the push-on finger 109 is first lowered, and the push-on rod 103 is then moved rearwardly, causing the push-on finger to engage the lowermost tube T (Fig. 1) and push it onto the spindle 8 which is in position to receive it (see description of spindle mechanism above). The stroke of the yoke 132 is made slightly longer than necessary to accomplish the positioning of the tube upon the spindle in order to insure a firm engagement between the neck of the tube and the burr 51 of the spindle pin 50. The latter portion of the stroke of the yoke 132 is taken by the coil spring 135, which transmits to the push-on rod 103 sufficient energy to force the tube T firmly into position on the spindle 8. The timing of the push-on mechanism is so regulated that the next forward movement thereof will occur just prior to, or simultaneously with, the next rotary movement of the turret 1, so that the push-on finger is taken out of engagement with the tube on the spindle and does not interfere with the movement of the turret. The movement of the turret replaces another empty spindle in position to receive a tube, and moves the tube, which has just been placed upon the preceding spindle as described above, to station B, there to be subjected to the operation of the trimming and end-finish mechanism.

Trimming mechanism

This mechanism is shown in detail in Figs. 15, 16, 17, and 20, while Fig. 8 best illustrates the means employed for moving the trimming tool into and out of operative position. Referring to Fig. 20, the trimming tool 201 may take the form of a straight-edged blade, as shown, and is adjustably mounted in a split tool holder 202 (see Fig. 17), in order that when a portion of the blade becomes dull the tool may be adjusted to present a fresh portion of its edge to the work. The tool holder is pivoted at 203 to a rod 204, which is adjustably retained by a bifurcated trimming lever 205. A pair of springs 202a and 202b serve to retain the tool holder in an appropriately tilted position. The rod 204 is locked in proper position within the trimming lever by means of a bolt 206. The trimming lever 205 is keyed to a rock shaft 207 which is journaled in suitable bearings formed in the tool unit head 32 (Fig. 20) and a bracket 208 (Fig. 16). By providing the rock shaft 207 with an elongated keyway 209 the trimming lever 205 is made adjustable to a variety of positions along the rod 207, according to the length of the tubes upon which the machine is operating, and may be locked in any position by means of a set screw 210 (Fig. 17).

Upon the forward end of the rod 207 is positioned a cam lever 211, which is bifurcated, as shown (Fig. 15), and may be clamped in suitable position upon the rod 207 by means of a bolt 212. 5 Journalled upon a stud 213 projecting from the opposite end of lever 211 is a cam roller 214 which cooperates with a cam 215. A coil spring 216 is secured at one end to a stud 217 upon the lever 211, and at the other end to a hook 218, 10 and operates to maintain the cam roller 214 in engagement with the cam 215. The latter is keyed to a shaft 219 (Fig. 8) which extends rearwardly into the shaft 142 and is secured, by means of a pin 220, to the latter shaft. The shaft 15 219 is journalled in suitable bearings 221 and 222, carried by the main frames.

As above described, in connection with the push-on mechanism, the shaft 142 is driven by the main motor 10, and the shaft 219 is therefore 20 similarly driven, and rotates the trimmer cam 215. It will be apparent from the shape of the cam 215 (see Fig. 15) that the lever 211 is periodically forced downwardly, rocking the rod 207 in a counterclockwise direction and causing the 25 trimming tool 201 to bear against the tube T (Fig. 16) and sever the rearward portion thereof from the main body, forming what is hereinafter called the "scrap". As described under the heading 30 "Spindle mechanism", the spindle and tube are revolved during this operation. Due to the form of the cam 215, the trimming tool is withdrawn from the work rapidly, and remains in its retracted position during a relatively extended period, including the interval during which the 35 turret 7 is rotating.

End-facing mechanism

This mechanism is shown in detail in Figs. 15-20 and 22. The end-facing operation takes 40 place simultaneously with the trimming operation just described, and at the same station (B). This operation results in opening the end of the hitherto closed neck of the tube T, and removing any 45 irregularities of the end surface thereof and putting a slight bevel thereon.

In connection with the trimming mechanism the shaft 219 and its driving means have been described. Referring to Fig. 16, it will be seen 50 that a bevel gear 225 is secured upon the shaft 219, by means of a set screw 226. Bevel gear 225 meshes with a second bevel gear 227 which is journalled upon a stud 228 projecting from a suitable bracket 229 secured to the tool unit head. Upon the stud 228 and, if desired, formed 55 integral with bevel gear 227, is a spur gear 230, which meshes with a second spur gear 231 which is keyed to a transverse cam shaft 232. Cam shaft 232 is journalled in suitable bearings 233 and 234 (Fig. 20) provided in the tool unit head. The cam shaft 232 carries, in all, four cams for 60 operating various ones of the finishing tools, including a cam 235 for operating the facing tool. The cam 235 is seen in profile in Fig. 22, together with its cooperating cam roller 236. The roller 236 is journalled upon an arbor 237 which 65 extends across a roller aperture 238 formed in a lever 239, the arbor being secured in place by a set screw 240. This construction may be seen in front elevation in Fig. 15. The facing lever 239 is journalled upon a short transverse arbor 70 241 which is suitably secured between projecting portions of the tool unit head.

An end facing tool 242 (Fig. 18) is mounted at the lower end of the facing lever 239 in a manner best illustrated in Fig. 23. The tool 242 75 is secured, by means of a pair of set screws 243,

in a tool holder 244. The latter is formed with a dovetail portion which is slidably mounted for vertical movement in a bifurcated slide 245. The tool is therefore adjustable vertically by loosening a clamping screw 246 and turning an adjusting screw 247. The slide 245 is likewise formed with a dovetail at its upper end, which is slidably mounted for horizontal movement in a bifurcated transverse slide 248. The tool is maintained in proper transverse adjustment by 10 means of a clamping screw 249. Transverse slide 248 is also provided upon its upper surface with a dovetail portion which is slidably mounted for movement in a direction parallel with the axes of the spindles, in a longitudinal slide groove 15 250 formed in the bifurcated lower end of the facing lever 239. Longitudinal adjustment of the tool 242 is secured by loosening clamping screw 251 and turning adjusting screw 252 (Fig. 22). Thus the end facing tool 242 is adjustable in three dimensions, i. e., vertically, transversely and longitudinally.

Referring to Fig. 18, it will be seen that the end-facing tool 242 has a V-shaped blade. The smaller or right-hand point of the blade is adapted to cut away the metal toward the center of the closed end of the tube neck, thus making an opening into the hollow interior of the tube. The larger left-hand portion of the blade serves to cut away irregularities of the end surface of 30 the tube neck, and, if desired, to bevel the same. These operations are performed while the tube and spindle are being revolved, as hereinbefore explained, and are brought about by the rearward or inward movement of the lower end of 35 the lever 239 and tool 242 under the compulsion of a coil spring 253, which is engaged between a hook 254, secured to the lever 239, and a hook 255 secured to a guide support 256, which will be hereinafter more fully described. The tension of spring 253 serves to maintain the cam roller 236 in constant engagement with the cam 235, and the movements of lever 239 and tool 242 are accordingly governed by the cam 235. As 40 is apparent from the shape of the cam (Fig. 22), the movements of the facing lever and tool are 45 relatively slight.

In order to insure accurate alignment of the tool with the tube as the lower end of the lever 239 moves towards the tube, suitable guide means 50 are provided. The guide support 256, above mentioned, is secured to the bottom of the tool unit head by any suitable means, as by the bolts shown (Fig. 20). Secured to the underside of the guide support 256 is a guide bar 257, which 55 projects forwardly slightly beyond the plane of the facing lever 239 (see Fig. 18). To a shoulder of the guide bar 257 is secured a strip 258 (Fig. 23) which extends downwardly beyond the shoulder of the guide bar to form a longitudinal 60 guideway 259. To the side of facing lever 239 adjacent the guide bar 257 is secured a plate 260 (Figs. 23 and 19). To a shoulder formed on the lower portion of the plate 260 is secured a tongue 261, which extends upwardly into the 65 guideway 259, and effectively prevents any lateral movement of the facing lever 239, which might otherwise occur, while permitting the longitudinal movements necessary to the operation of the end-facing mechanism. Due to the 70 shape of the cam 235, the tool 242 is urged slowly against the work during most of the period when the turret 7 is stationary, and is retracted more rapidly just before the turret moves to advance the tube to the next station (C).

Threading mechanism

This mechanism is shown in detail in Figs. 15, 20, and 21. A threading tool 301, which is preferably of the form shown, is carried at the lower end of a lever 302, by means hereinafter described. A cam roller 303 is arranged in an aperture in the lever in a manner similar to that described above in connection with the end-facing mechanism. It is urged by a spring 305 into engagement with a cam 304 to cause a short oscillatory movement of the lever during rotation of the cam, just as in the case of the lever 239 described above. The cam 304 is keyed to the transverse cam shaft 232, which is driven in the manner previously described.

Also keyed to the cam shaft 232 is a tool lifting cam 306, which cooperates with a cam roller 307 mounted at the lower end of a lifting lever 308, of bell crank form. An arbor 310, upon which lever 302 is supported, is mounted in the forward end of the horizontal arm 309 of the lifting lever. As will be seen in Figs. 15, 17, and 21, the arbor 310 is square in cross-section throughout that portion which extends through the arm 309, but is cylindrical in cross-section in its projecting portions. The lever 302, which is bifurcated, is journaled upon these projecting cylindrical portions of the arbor 310, as shown in Fig. 15, and in broken lines in Fig. 21. For convenience in assembling, the end of the arm 309 is provided with a square notch to receive the arbor 310, which is then locked in place by means of a cover plate 311 and bolts 312. By reason of the construction described, the arm 309 may be lifted by the lifting cam 306, thus raising the lever 302 and tool 301, without disturbing the horizontal relationship between the tool 301 and the tube upon which it is operating. The lifting cam roller 307 is maintained in engagement with the lifting cam 306 by means of a spring 313, which is connected between a hook 314, secured to the lifting lever 308, and a hook 315 secured to the guide support 256.

The threading tool 301 is mounted upon a pin 316 (Fig. 21) which extends through the bifurcated lower end of a tool holder 317, and is secured thereon by a nut 318. The pin 316 is adjustable longitudinally by means of an adjusting screw 319, and is locked in place by means of a clamping bolt 320. The tool holder 317 is secured to the threading lever 302 by means of a bolt 321, and is adjustable vertically by means of an adjusting screw 322, the bolt hole 323 being elongated so as to permit of this adjustment. To prevent lateral movement of the threading lever 302, the latter is restrained between the guide bar 257, hereinbefore described, and a second longitudinally-extending guide bar 324, secured to the guide support 256. In order to prevent wearing of the main body of the lever 302, wear plates 325 and 326 (Fig. 15) are secured at the sides thereof, in sliding engagement with the guide bars 257 and 324.

It will be noted that the threading tool 301 is preferably in the form of a disc with a sector removed, as seen in Fig. 15. When the point of the tool becomes dulled the disc may be removed from the machine and a small additional sector cut away, thus forming a new cutting point. The entire periphery of the tool, of course, is edged.

In the operation of the threading mechanism, assuming that the turret 7 has just come to rest, and that the spindle at the threading station (C) is being revolved by the means hereinbefore de-

scribed, the tool 301 is in its lowered position, due to the position of the lifting cam 306, and is in engagement with the outer end of the tube neck which is to be threaded, due to the position of the threading cam 304. As the spindle and tube revolve, the threading tool is moved gradually rearward by the action of the spring 305 and threading cam 304 and the tube neck is threaded. The pitch of the threads formed depends upon the speed of rotation of the spindle, which is adjustable independently of the speed of movement of the tool by means described above in connection with the main drive.

It will be noted that the movement of the cutter during the cutting operation is not strictly rectilinear, but due to the length of the lever 302 and the short arc of movement required to cut the full thread, the deviation from a straight line is negligible. Furthermore, the location of the pivotal center of the lever 302 with relation to the neck of the tube being threaded is such that the entire cutting movement of the cutter is slightly on the up-swing, so that in going from the end of the neck toward the body of the tube it is shifted a slight distance away from the axis of the tube. This results in the production of a thread which becomes gradually tighter as a cap is secured over it.

When the tool 301 reaches its rearward limit (Fig. 21) the lifting cam 306 and spring 313 cooperate quickly to lift the tool out of engagement with the tube, and immediately after the threading cam 304 and spring 305 move the lever 302 and tool 301 forward. As the turret again moves to advance the succeeding spindle to the threading station, the threading lever 302 and tool 301 are lowered to operating position by the action of the spring 313 and lifting cam 306. This operating cycle is continually repeated so long as the cams 304 and 306 are operated.

Burr-removing mechanism

This mechanism, which is quite similar to the end-facing mechanism previously described, is illustrated in Figs. 15, 17, 20, 24, and 25. The burr-removing tool 401 (Fig. 17) is similar to the end-facing tool 242, except that it is preferably so shaped as to put a pronounced bevel on the outer edge at the forward end of the tube neck, and has no point which projects into the neck of the tube, but in place thereof has a blade portion which extends straight across the face of the tube neck, to cut at a right angle to the axis of the tube. This operation, of course, removes any burr left at the end of the tube neck by the threading tool.

The tool 401 is mounted on a burr-removing lever 402 (Fig. 24) in a manner identical with the mounting of the end-facing tool, hereinbefore described (see Figs. 23 and 25), except that, looking from the front of the machine (Figs. 1 and 15) the burr-removing tool 401 extends to the left of the lever 402, while the end-facing tool 242 extends to the right of its lever 239. This arrangement is not essential, but is convenient in order to avoid interference with the spindles during rotation of the turret, and for other reasons involved in the design of the machine.

The burr-removing lever 402 is journaled upon an arbor 403 (Fig. 15) which is mounted in the tool unit head and held against lateral displacement by the cooperation of a groove 404 in the arbor, with a pointed bolt 405 carried by a portion of the frame. An arbor 406 (Fig. 24) is mounted between rearwardly projecting ears 407 of the lever 402, and locked by means of a set

screw 408. A cam roller 409 is journalled upon the arbor 406, for engagement with a cam 410 which is keyed to the transverse cam shaft 232. The cam roller is maintained in engagement with the cam by means of a spring 411, which is connected between a hook 412, secured to the lever 402, and a hook 413 (Fig. 20) secured to the tool unit head.

By means of the cam 410 and spring 411 the lever 402 and tool 401 are controlled so that the tool is moved out of the way when the turret is about to rotate and is moved slowly into engagement with the work when the turret stops. The spindle, at this station (D) is revolved by means hereinbefore described.

By a system of dovetailed slides the tool 401 is made adjustable in three dimensions relative to the lever. Thus a slide 414 may be adjusted along the lower end of lever 402 in the direction of the spindle axis by means of a screw 415 and it may be locked in place by a screw 416. A second slide 417 is arranged to be shifted on the slide 414 in a horizontal direction at right angles to the direction of movement of slide 414 and may be locked by a clamping bolt 418. A third slide 419 is shiftable vertically on the slide 417 by means of an adjusting screw 420 and is clamped in set position by a bolt 421. The tool 401 is carried between jaws of the slide 419 and is secured by set screws 422.

Coating mechanism

The coating mechanism is best illustrated in Figs. 1 and 26. In order that the coating material may be constantly agitated, even when the machine as a whole is temporarily out of operation, and for other reasons having to do with the general design and construction, the coating mechanism is powered by a separate motor 12 (Fig. 1). Motive power is transmitted to the coating mechanism by a belt 501 which runs over a pulley 502 on the motor shaft and a driven pulley 503 (Fig. 26) which is keyed to a shaft 504 of a speed reduction unit 505. The output shaft 506 of the speed reduction unit 505 is coupled through a universal joint connection to a shaft 507 upon which are secured a friction disc 508 and a coating roll 509. The shaft 507 is journalled in suitable bearings in a coating stand 510, which is adjustably mounted upon a bed plate 511 (Fig. 1) secured to the frame 13 of the machine. Adjustment of the coating stand is secured by means of an adjusting screw 512.

A color pan 513 is supported upon the coating stand and is adapted to contain the coating material, which may be supplied by any suitable means. A color roll 514 is journalled in suitable bearings supported by the coating stand 510, and is arranged to be partly submerged in the coating material contained in the color pan 513. The color roll 514 is adjustable laterally by means of adjusting screws 515 acting upon the roll bearings, as shown in Fig. 3. A transfer roll 516 is likewise journalled in adjustable bearings in the coating stand 510, and is adjustable laterally by means of adjusting screws 517. The transfer roll 516 is arranged to engage frictionally both the color roll 514 and the coating roll 509. Shaft 507 is connected with the shafts supporting the rolls 514 and 516 by means of gearing 516a (Figs. 4 and 5) and thus provides the power for rotating all of the rolls and brings about the transfer of a suitable amount of coating material from the roll 514 to the roll 509. The coating roll, which may have a soft surface of gelatin or other suitable

material, is adapted to transfer a film of coating material to the surface of the tube upon the adjacent spindle. By lateral adjustment of the entire coating stand and associated mechanism the coating roll is brought into a relatively loose engagement with the tube for the most satisfactory transfer of the coating substance.

As a result of this adjustment the friction disc 508, which is of slightly larger diameter than the coating roll, is brought into frictional engagement with the spindle 8 which is at the coating station (E), with the result that the spindle is revolved at the proper speed to effect a peripheral speed of the tube T substantially equal to that of the coating roll 509. As shown in Fig. 5, the friction disc 508 engages the spindle at a point forward of the forward turret plate 54, but rearward of the tube and scrap upon the spindle.

From the foregoing description it is believed that the operation of the coating mechanism will be obvious. It constitutes a unit readily separable from the remaining structure of the machine and driven independently of but in co-operation with the other operating devices.

Capping mechanism

This mechanism is illustrated in Figs. 1-8 and 28-34, inclusive, and comprises means for feeding screw caps (of any type usually employed for closing collapsible tubes of the nature under consideration), feeding a strip of cork, punching out cork gaskets, inserting the gaskets in the caps, screwing the caps onto the necks of the tubes as they are successively presented by the rotation of the turret, and cutting up and disposing of the cork scrap remaining after the gaskets are punched out of the strip. The cap-feeding means will first be described.

Referring to Fig. 3, it will be observed that a small pulley 601 is secured upon a shaft 602, upon which is also fixed the large gear 23 which is a member of the gear train driven by the main motor 10 for driving the Geneva mechanism as hereinbefore described. A belt 603 is driven from the pulley 601 and in turn drives a pulley 604, keyed upon a short shaft 605 which is journalled in a suitable bearing 606 (Fig. 5) supported upon the frame of the machine. Keyed upon the opposite end of the shaft 605 is a sprocket 607, which drives a chain 608. A sprocket 609, driven by the chain 608, is secured upon a short shaft 610, which is journalled in a bearing 611, supported upon a suitable bracket 612 (Figs. 3 and 4). Upon the opposite or forward end of shaft 610 is secured a pinion 613, which meshes with a spur gear 614, fixed upon a short shaft 615. The latter is journalled in bearings 616 and 617, also supported on the bracket 612.

Secured upon the shaft 615 is an eccentric disc 618 (Fig. 3), which cooperates with a roller 619, journalled at one end of a yoke 620, to cause intermittent reciprocation of the yoke 620 and a connecting rod 621. A rocker arm 622 is connected to the opposite end of the rod 621 by means of a yoke 623 and pin 624, the arm being secured upon a rock shaft 625 by means of a clamping screw 626. An arm 627 is also secured upon the rock shaft 625 and is engaged by one end of a coil spring 623, the other end of which is fastened to the frame of the machine (see Fig. 4). The rock shaft is journalled in brackets 629 and 630, secured to the wall of a cap supply hopper 631 (Fig. 5). A gear sector 632 (Figs. 1 and 5) is secured upon the rock shaft 625 and meshes with a toothed rack 633 which is mounted for ver-

tical reciprocation between a guide plate 634 and the forward wall of a cap feed hopper 635. The latter is located forwardly of the cap supply hopper 631 and is supplied with caps through an opening at the bottom of the wall between the hoppers, controlled by a gate 636. The bottoms of the hoppers are inclined forwardly at a suitable angle to permit the caps to move by gravity into the feed hopper.

Referring to Fig. 2, a hopper plate 637 is secured to the rack 633 by means of a knurled screw 638, but is spaced from the rack by a spacer plate 639, so that the hopper plate lies inside the forward wall of the cap feed hopper 635. The upper edge of hopper plate 637 is inclined upwardly from right to left (see Fig. 1), and is provided with a groove 640 for the purpose of accommodating a number of caps C' in the position illustrated in Fig. 2. It will be noted that due to the form of the top edge of the plate the caps, when properly received by the plate, will incline slightly toward the front and the apron of the cap will engage and roll along the inner edge of the plate.

It will be understood that by reason of the mechanism described the hopper plate 637 will be periodically reciprocated vertically within the hopper 635. As the hopper plate descends into the supply of caps to a point somewhat below the bottom of the hopper and then ascends again, a number of caps will lodge in the groove 640, and when the hopper plate reaches its uppermost position (Fig. 1) the caps will roll into a chute 641 and will be delivered by gravity, one at a time, to the lower end of the chute, where they are provided with cork gaskets by the means presently to be described. Caps which are not properly presented to the plate 637 will simply fall away as the latter rises through the supply in the hopper. This includes any caps that may be faced in the wrong direction, since their flanges will not be engaged in the groove 640. The knurled screw 638 provides a convenient means for quickly disconnecting the plate 637 from the operating rack whenever desired.

A reel 642 containing cork in the form of a thin and narrow strip 643 is rotatably mounted upon a bracket 644 (Fig. 1), means being provided for imposing suitable friction upon the reel to insure a proper tension upon the cork strip. The cork strip 643 is passed over a guide pulley 645 (Fig. 5) and is then carried through guides 648, between a pair of feed rollers 646 and 647 (Fig. 29), into a narrow slot formed between a stripper plate 649 and a die plate 650. Feeding of the cork strip occurs intermittently by means of the frictional engagement thereof between the feed rolls 646 and 647. The feed roll 646 is intermittently rotated by means illustrated in Figs. 6 and 7, while feed roll 647 is driven from the roller 646 by means of gearing 646a.

Feed roll 646 is fixed upon a shaft 651 journaled in a bracket 652. Upon the upper end of shaft 651 is fixed a ratchet 653. A pawl yoke 654 is journaled upon shaft 651 and carries a pawl 655. The yoke 654 is connected by a link 656 with a rocker arm 657, which is pivoted at 658 and is connected by means of a yoke 659 with a connecting rod 660. The latter is journaled, at its other end, upon a crank pin 661 which is secured to a combined unit 662 comprising a cork punch cam and a cork feed crank. This unit is secured upon a shaft 663 upon the opposite end of which is secured a bevel gear 664 (Fig. 4) which meshes with a bevel gear 665 secured upon the shaft 138 (Fig. 3) hereinbefore

mentioned. Shaft 138 is driven from the main motor 10, by means already described.

It will be understood from the foregoing that by means of the connections described the connecting rod 660 is given a reciprocatory movement once upon each advance of the turret, which results in the intermittent rotation of the cork feed rolls 646 and 647, thus feeding the cork strip 643 step-by-step.

The relation of cap, cork strip and cork punch is best seen in Figs. 29 and 30. As the cork strip 643 advances between the stripper plate 649 and die plate 650 it passes behind a die 666. During each interval of rest a punch 667 is reciprocated to punch a disc or gasket from the cork strip. The punch 667 is mounted in the forward end of a hollow punch holder 668 which is slidably mounted in a bracket 669. Threaded to the rear end of the punch holder 668 is a stop nut 670 for limiting the forward movement of the punch and punch holder. Slidably mounted within the hollow punch holder 668 is a pusher rod 671 which will be referred to hereinafter. A bifurcated punch finger 672 is secured to an angle member 673 which is supported upon a reciprocating rod 674. The prongs of the finger 672, extend above and below the pusher rod 671 and abut against the rear end of punch holder 668, for the purpose of moving the latter forwardly to effect its punching action when the rod 674 is reciprocated by means to be described.

The connecting rod 674 is slidably mounted in brackets 675 and 676 (Figs. 6 and 7) and is provided at its rear end with a cam roller 677 for cooperation with the cam 662. A spring 678, connected between the rod 674 and bracket 676 serves to maintain the roller 677 in constant engagement with the cam 662, so that the movement of rod 674 and punch finger 672 are governed by the cam. The length of the rod 674 may be varied to adjust the operation of the parts, by forming it in two sections and connecting these by a link 674a having elongated slots cooperating with suitable bolts carried by the rod sections.

A threaded stud 679, secured in the pusher rod 671, extends through a slot 680 in the wall of the punch holder 668, and serves the double purpose of providing a stop for the forward movement of the pusher rod and of serving to retract the punch holder 668 by the rearward movement of the pusher rod 671, to be described.

Referring to Fig. 6, it will be seen that the pusher rod 671 has secured thereto a sleeve 681, into which is threaded the stem of a hollow coupling member 682, containing a coil spring 683. A reciprocal rod 684 is slidably mounted in a suitable bearing 685 and carries at its forward end a piston 686 which extends into the hollow coupling member 682 and engages the coil spring 683. A pin 687, secured to the piston 686, extends through a slot 688 in the wall of the coupling member 682, and limits the extent of relative movement between the piston and coupling member. A cam roller 689 arranged at the rear end of the connecting rod 684 cooperates with a cam 690 secured upon the cam shaft 663 to control the reciprocatory movements of the rod 684. A spring 691, connected between suitable means secured to the bearing 685 and the connecting rod 684, serves to maintain the cam roller 689 in constant engagement with the cam 690. The means by which cam shaft 663 is driven have been already described. Suitable adjustment of the length of the connections between the rod 684 and the cam 690 will insure the proper timing of the reciprocating movement of the rod 684.

671 and cam 690 may be made through the connection of the stem of member 682 with the sleeve 681 and the connection of piston 686 with rod 684.

- 5 From the foregoing it will be understood that connecting rod 684 and its associated mechanism are given an intermittent reciprocatory motion, the nature of which will be seen from the profile of cam 690 (Fig. 7), thus advancing and 10 retracting the pusher rod 671. Threaded into the forward end of the latter is a cork pusher 692, which is slidably within the hollow punch 667. The time relation between the movements of the punch 667 and the pusher 692 is such that the 15 punch is advanced, carrying with it the pusher 692 by reason of the inter-connection effected by the stud 679 and the slot 680, to punch out a cork gasket and move it forwardly into the die 666. The forward movement of the punch is 20 then arrested, in a position determined by the throw of cam 662 and by the stop nut 670, but the pusher continues to move under the action of cam 690, forcing the gasket into the screw cap which happens to be at the bottom of the 25 chute 641, and pushing the cap out of chute 641 into a chuck 693 (Fig. 30), to be conveyed to and placed upon a tube T upon the adjacent spindle, as will be hereinafter explained. It will be understood that this movement of the pusher 30 takes place under the yielding force of the spring 683.

In order to dispose of the balance of the cork strip 643 after the gaskets are punched out, means are provided for cutting it up and blowing 35 the scraps, by means of an air jet, into a scrap chute. Referring to Fig. 29, a scrap punch holder 694 is secured in a connecting arm 695 carried by the pusher rod 671, and is reciprocated with the latter. Secured in the forward end of the 40 scrap punch holder is a scrap punch 695 which cooperates with a scrap die 697, carried by the die plate 650, to sever a short piece from the cork strip at each forward movement of rod 671. The scrap punch holder and scrap punch 45 are provided with air passages 698 and 699, supplied with compressed air by a hose 701 connected with any suitable source of supply. When a piece of scrap is severed it is conveyed, by the air jet issuing from the scrap punch through the 50 passage 699, to a scrap chute 702, whence its disposal may be effected in any suitable manner.

The chuck 693 is best illustrated in Figs. 31 and 32. The cap gripping means comprise three segmental jaws 703, pivoted, as at 704 (Fig. 31) 55 to a plunger 705 and drawn together at their free ends by an encircling coil spring 703a. The plunger 705 is slidably mounted in bushings 706 and 707, carried by a capping lever 708 (Fig. 28) and is keyed with relation to bushing 707, 60 as at 709, to prevent rotation. A small spring 710 acts to urge the plunger 705 outwardly toward the spindles. A stop nut 711 limits the outward relative movement between the plunger 705 and capping lever 708. Upon the outer end 65 of the plunger 705 is threaded a nut 712 which contains a bushing 713 of leather or other suitable friction material. Extending entirely through the plunger 705 and nut 712, and slid- 70 able therein, is a push rod 714 provided with a head 715. The bushing 713 frictionally resists sliding of the push rod 714, but this friction is adapted to be overcome by the application of a slight force. When the cap is about to be pushed into the chuck, in the manner already described, the push rod 714 is in a forward position, with

its head 715 ready to be engaged by the top of the cap, and as the cap is pushed into the chuck the push rod is forced back against the friction of the bushing 713. The presentation of a flat surface to the top of the cap before it is carried 5 into the chuck jaws and the yielding opposition to the movement of the cap into the chuck prevents the cap from rocking and insures accurate positioning of the cap within the chuck. This is of great importance in screwing the cap 10 onto the tubes, as otherwise the threads would be crossed and destroyed, and the operation would in many instances be unsuccessful. Rearward movement of the push rod 714 is, of course, limited by the plunger 705 which is resiliently 15 pressed forwardly by the spring 710.

After a cap is placed in the chuck as shown in Fig. 30, the chuck is moved, by means to be described, to a position in front of the spindle that is at the moment adjacent station (F) as 20 shown in Fig. 31. As the spindle is rotated (by means hereinbefore described) the chuck is moved inwardly to bring the cap into engagement with the neck of the tube upon the spindle, and the cap is thus threaded onto the tube. When 25 the cap is substantially all the way on, it is tightened in place by the friction between the belt 42 (Fig. 9), which is moving, and the pulley 15 of the spindle, which is prevented from further rotation by the grip of the jaws 703 upon the 30 cap.

Referring to Fig. 6, it will be seen that the capping lever 708 is secured upon the end of a longitudinally extending rock shaft 716 which is mounted slidably and rotatably in bearings 717, 35 719 and 720. By means of a coil spring 721 interposed between a collar 722 and the bearing 717, the rock shaft 716 is biased toward its rearward position. Keyed to the rock shaft 716 near its rearward end but slidable relative thereto is a 40 sector plate 723 (Fig. 33). Connected with the plate 723, by means of the arcuate slot and bolts shown, is another plate 723a which is connected by means of a link 724 with a rocker arm 725 pivoted upon a stud 726. A cam roller 727 is 45 journaled upon a stud 728 of the rocker arm, for cooperation with a cam 729, secured upon the cam shaft 663. A spring 730, connected between the upstanding portion of arm 723a and a fixed stud 731 (see Fig. 3), serves to rock the plates in a 50 clockwise direction (Fig. 33) and maintains the cam roller 727 in engagement with the face of the cam 729. It will be understood that by means of the mechanism described the capping chuck is intermittently moved laterally from the position of Fig. 30, adjacent the cap chute, to the position of Fig. 31, in front of the spindle (see also Fig. 28). It will be apparent that the connection between the arm 723a and sector plate 723 is such that the zone of movement of the shaft 716 and the arm 708 may be varied to insure alinement of the chuck with either the cap at the bottom of the chuck or with the spindle. In the construction as illustrated the chuck is alined with the spindle when the roller 727 is upon the high part 55 of the cam 729. To properly register the chuck with the cap at the bottom of the chute a set-screw 730a carried by a bracket 730b is adapted to be engaged by a striker plate 708a on the chuck arm. In this way the movement of the 60 chuck arm by the spring 730 as the roller 727 rides down to the low-part of cam 729 may be definitely limited independently of the depth of the cam. It will be understood that this construction permits accurate positioning of the 65 70 75 75

chuck at the two ends of the movement of arm 708 without extreme accuracy in the formation of cam 729. This also permits adjustment to take care of wear.

5 The longitudinal movement of the chuck is brought about by the mechanism of Fig. 34. A cam 732, keyed to cam shaft 663, cooperates with a cam roller 733, carried by a rocker arm 734. The latter is pivoted at 735 (see Fig. 7) and is provided at its bifurcated upper end with a split collar 736 which slidably engages an annular groove 737 (Fig. 34) formed in a collar 738 secured upon the rock shaft 716 by means of a taper pin 739. From the foregoing it will be apparent that the shaft 716 and chuck 693 will be given a periodic longitudinal movement for the purpose hereinbefore explained. It will be understood that the cams 729 and 732 are suitably coordinated so that when the chuck is rocked into position to receive a cap from the bottom of the chute by the action of pusher rod 692, it will be held forwardly against the action of spring 721; after the cap is inserted in the chuck it is rocked into line with the spindle and then moved toward the spindle. This latter movement may be rapid at first, until the cap engages the tube, and it is then more slow to correspond with the advance of the cap upon the threaded neck. After the cap has been applied to the tube, the chuck is moved outwardly, releasing the cap, and is then rocked to its position before the cap chute (Fig. 30). This cycle is continuously repeated.

In order that the push rod 714 may be in its forward position when the chuck is to receive the next cap, an arm 740 (Figs. 28, 31) is pivoted on a bracket 741, providing a stop against which the push rod 714 strikes as the chuck 693 is moved outwardly from the spindle, thus causing the push rod to assume its forward position in the chuck. When the push rod is in its rearward position, after the chuck has received the next cap, the push rod of course extends beyond the plane of the arm 740. When the chuck is rocked to its cap-applying position, the push rod strikes the arm 740 and rocks it downwardly against the tension of a spring 742 (Fig. 28). As the chuck is then moved inwardly toward the spindle the arm 740 is released and moves upwardly against an adjustable stop 743, where it is again in position to engage the end of push rod 714 upon the next outward movement of the chuck.

For convenience of introducing a new strip of cork between feed rolls 646 and 647, manual roll-releasing means shown in Fig. 29 are provided. The feed roll 647 is mounted on a shaft 647a which is journaled in upper and lower bearings 744 (Fig. 7). Each of the bearings 744 is slidably mounted on a pair of studs 745 (Fig. 29), and is urged toward feed roll 646 by coil springs 746 which are interposed between the bearings 744 and a plate 747 mounted on the studs 745. A pair of pull rods 748 are threaded into the bearings 744 and extend outwardly through the plate 747, where they are connected by a vertical cross-bar 749. The cross-bar 749 is urged outwardly, by small springs 750, against nuts 751.

A bracket 752 is secured to the plate 747, and a handle 753 is pivoted therein by a stud 754. Handle 753 is in the form of a bell crank, and the short arm 755 projects into the space between the plate 747 and cross-bar 749. It is apparent that by gripping the handle 753 and moving it to the left (Fig. 29) the pull rods 748,

bearings 744, and feed roll 647 are forced outwardly, compressing springs 746 and permitting a new strip of cork to be introduced between the feed rolls. Releasing the handle 753 will cause the feed roll 647 to move inwardly again, gripping the cork strip against the feed roll 646.

In order to insure the presence of an adequate supply of caps in the cap chute 641 when the machine is started up, and at all times thereafter, a handle 756 (Figs. 1, 4) is secured upon the forward end of the rock shaft 625. By manually moving the handle downwardly and releasing it the hopper plate 637 (Figs. 1, 2) is moved down into the supply of caps and is raised by spring 628 (Fig. 4) to provide the chute 641 with a supply of caps, in the manner hereinbefore described. This manual operation can, of course, only be effected when the eccentric 618 is out of engagement with the roller 619 (Fig. 3).

All of the operations performed by the machine upon the tubes and caps and the means employed for these operations have now been described. When the tube arrives at either station G or station H, it may be removed from the spindle by any suitable means, manual or otherwise. There remains only to remove the scrap from the spindle to place it in condition to receive another unfinished tube. The scrap, it will be understood, is left on the spindle by the trimming operation at station B and can not be removed until after the finished tube is removed.

Scrap-removing mechanism

This mechanism may be seen in Figs. 1, 3, 4, 5, 35 and 42-45. In Fig. 44 will be seen the ring of scrap 801 remaining upon the spindle 8 as it arrives at station K. A bifurcated scrap removing finger 802 straddles the spindle and is adapted to be moved, by means to be described, in such a way as to strip the scrap ring 801 from the spindle and deposit it in a scrap chute 803 (Fig. 35).

Referring to Fig. 3, it will be seen that a yoke 804, pivoted at one end as at 805, is oscillated by an eccentric block 806 in a manner similar to the push-on yoke, as hereinbefore explained. The yoke 804 is connected by links 807 (Figs. 4 and 5) with a collar 808 threaded upon a tube 809. The tube 809 is slidably mounted in suitable bearings 810 and 811 provided in brackets 812 and 813 secured to the main frame 13, and carries at its forward end a head 814 (Figs. 44 and 45) provided with spaced brackets 815 and 816. Two short shafts 817 and 818 are journaled in the brackets 815 and 816. A scrap removing lever 819 is keyed to shaft 817, as are also a pinion 820 and a stop lever 821 (Fig. 44). A second pinion 822 is keyed to shaft 818, and meshes with pinion 820. Also keyed to shaft 818 is a friction lever 823 which is pivoted at 824 to a friction bar 825. The latter is slidably mounted in a drag device 826 supported on the bracket 813 (Fig. 43).

The drag device 826 is of the general nature hereinbefore described in connection with the push-on mechanism, and consists of upper and lower members provided with leather friction elements 827 and 828, and means for adjusting the pressure of the latter upon the friction bar 825 and thereby varying the effective friction forces therebetween. The adjusting means comprise a back plate 829, upon which the friction element 827 is mounted, a plunger 830 secured to the back plate, a spring 831 and an adjusting screw 832 for varying the pressure of the spring. A nut 75

833 is provided for locking the adjusting screw 832.

The scrap removing finger 802 is slidably mounted in lever 819, and resilient means are provided for urging the finger 802 toward its outer position, such means comprising a plunger 833, spring 834 and adjusting screw 835. In this manner the pressure of the contact between the finger 802 and spindle 8 may be controlled. The movement of the finger 802 lengthwise of the lever 819 is limited by a stud 836 which extends through a slot 837 in the finger.

Due to the oscillation of the yoke 804, the tube 809 is given reciprocatory motion. Assuming the mechanism to be in the condition illustrated in Fig. 44, the tube is moved toward the left, causing the finger 802 to engage the scrap ring 801 and strip it from the spindle 8. As the tube 809 reaches the end of its stripping movement and starts back toward the right, the friction of the device 826 upon the friction bar 825 causes it to be retarded, rotating pinion 822 in a clockwise sense, which causes a counter-clockwise rotation of pinion 820 and shaft 817, moving the finger 802 quickly into the position of Fig. 45. This rotation of the shaft 817 is arrested by engagement of the bottom side of lever 819 with a portion of lever 823, at which time the parts all move in unison with the tube 809.

Ordinarily the reciprocatory movement of the finger 802 will carry the scrap ring 801 from the end of the spindle and deposit it in the mouth of the scrap chute 803 (Fig. 35), which is spaced some distance from the end of the spindle. However, if the stroke of the finger is not sufficiently long to strip the ring completely from the spindle the sudden rocking of the finger, in the manner explained, may serve to complete the stripping action. Incidentally, the length of the stroke of the stripper finger may be varied by adjusting the eccentricity of the block 806 by means of the screw shown in Fig. 5. The position of the stroke may be varied by adjusting the collar 808 relative to the threaded portion of the rod 809. The finger remains in the tilted position of Fig. 45 and travels with the tube 809 until the retractive movement of the mechanism causes the stop lever 821 to engage an adjustable stop 838 threaded into the bracket 813, resulting in a clockwise movement of the stop lever 821, lever 819 and finger 802. This action places the finger 802 astraddle the succeeding spindle, which has arrived at station (K) during the interval of such return movement of the scrap removing mechanism, and the movements described are repeated. The rotation of stop lever 821 and shaft 817, of course, results also in forcing the friction bar 825 rearwardly to its starting position (Fig. 44).

In order to prevent the scrap ring from falling between the spindle end and the scrap chute 803, the latter is provided with a lip 839 (Fig. 5) which extends nearly to the plane of the spindle end, and is adapted to receive the falling scrap ring and deflect it into the chute. The chute may be constructed in any suitable manner, and is mounted upon the main frame 13 by means of brackets as shown (Fig. 35).

It is believed that the construction and operation of the entire machine and all its component parts will be easily understood from the foregoing description, and that a recapitulation of the operation of the machine may be omitted. It should be observed that provisions are made throughout the machine for the adjustment of

the various operative parts so that the machine may readily be adapted for the handling of tubes of different lengths and diameters and the parts may be brought into proper registry at all times.

The terms and expressions employed in the foregoing specification are used for purposes of description and not as limitations and it is not my intention to be restricted to the particular construction disclosed, many variations of which may be made within the scope of my invention.

I claim:

1. In a machine of the character described, in combination, a turret, a plurality of spindles journaled in said turret, means for giving said turret an intermittent rotary motion whereby said spindles are successively presented at a series of operating stations, and means effective as the spindles are brought to the various operating stations for rotating said spindles at different speeds in the same direction at different stations.

2. In a machine of the character described, in combination, a turret, a plurality of spindles journaled in said turret, means for rotating said spindles at a plurality of independently variable, different speeds, and means for giving said turret an intermittent rotary motion whereby said spindles are successively presented at a series of operating stations, said first mentioned means being effective as the spindles are brought to the various operating stations to drive the spindles at different speeds at different stations.

3. In a machine of the character described, in combination, a turret, a plurality of spindles journaled in said turret, means for rotating certain of said spindles at a given speed, means for simultaneously rotating other of said spindles at other speeds, means for independently varying said speeds, and means for giving said turret an intermittent rotary motion whereby said spindles are successively presented at a series of operating stations, said first and second mentioned means being effective upon different spindles as they are brought to different operating stations.

4. In a machine of the character described, in combination, a turret, a plurality of spindles journaled in said turret, a motor, a countershaft driven by said motor, means associated with said countershaft for rotating said turret, separate means associated with said countershaft for rotating one of said spindles, other means associated with said countershaft common to a plurality of other of said spindles for rotating the same, and means for independently varying the driving speeds of said separate means and said other means.

5. In a machine of the character described, in combination, a turret, a plurality of spindles journaled in said turret, a motor, a countershaft driven by said motor, means associated with said countershaft for rotating said turret, separate means associated with said countershaft for rotating said spindles, means for regulating the speed of said countershaft, and separate means for regulating the speed of said spindles.

6. In a machine of the character described, in combination, a turret, a plurality of spindles journaled in said turret, a motor, a main countershaft driven by said motor, means associated with said main countershaft for rotating said turret, a secondary countershaft driven by said main countershaft, means associated with said secondary countershaft for rotating said spindles, means for regulating the speed of said main countershaft, and separate means for regulating the speed of said secondary countershaft.

7. In a machine of the character described, in combination, a turret, a plurality of spindles journaled in said turret, a pulley associated with each of said spindles, a motor, a main countershaft driven by said motor, a secondary countershaft driven by said main countershaft, a belt driven by said secondary countershaft, and means for rotating said turret to bring said pulleys successively into engagement with said belt. 5
- 10 8. In a machine of the character described, in combination, a turret, a plurality of spindles journaled in said turret, a pulley associated with each of said spindles, a motor, a main countershaft driven by said motor, a secondary countershaft driven by said main countershaft, a belt driven by said secondary countershaft, means for regulating the speed of said belt, and means for rotating said turret to bring said pulleys successively into engagement with said belt. 10
- 15 9. In a machine of the character described, in combination, a turret, a plurality of spindles journaled in said turret, a pulley associated with each of said spindles, a motor, a main countershaft driven by said motor, a secondary countershaft driven by said main countershaft, a belt driven by said secondary countershaft, means for regulating the speed of said belt, means for rotating said turret to carry said pulleys successively into engagement with said belt, and means for 20 regulating the speed of said belt.
- 20 10. In a machine of the character described, in combination, a turret, a plurality of spindles journaled in said turret, a pulley associated with each of said spindles, a motor, a main countershaft driven by said motor, secondary countershafts driven by said main countershaft, belts driven by said secondary countershafts, and means for rotating said turret to bring said pulleys successively into engagement with each of 25 said belts.
- 25 11. In a machine of the character described, in combination, a turret, a plurality of spindles journaled in said turret, means for presenting said spindles successively at a series of operating stations, means for rotating said spindles at a given speed at certain of said stations, means for rotating said spindles at a different speed as they are carried to another station, and means for varying the ratio of said speeds. 30
- 30 12. In a machine of the character described, in combination, a turret, a plurality of spindles supported thereon, means for positioning work pieces on said spindles, means associated with each of said spindles for gripping a work piece to retain it thereon, means for rotating said spindles through a predetermined cycle, and separate rockable means associated with each spindle for releasing said work piece from said gripping means in a portion of said cycle. 35
- 35 13. In a machine of the character described, in combination, a turret, a plurality of spindles supported thereon, means for positioning work pieces upon said spindles, separate means associated with each of said spindles for gripping a work piece to retain it thereon, means for rotating said turret, and separate rockable means associated with each spindle for temporarily releasing said gripping means successively at a predetermined point in their movement with said 40
- 40 14. In a machine of the character described, in combination, a turret, a plurality of spindles supported thereon, a retractile gripping member associated with each of said spindles, means for positioning work pieces on said spindles, means for maintaining said gripping members normally in position to engage said work pieces, and a rotatable cam element associated with each spindle for retracting said gripping members to release said work pieces. 5
- 45 15. In a machine of the character described, in combination, a turret, a plurality of spindles supported thereon, a retractile pin associated with each of said spindles, means for rotating said turret, and means including a rockable cam for each spindle for temporarily retracting said pins successively at a predetermined point in their movement with said turret. 10
- 50 16. In a machine of the character described, in combination, a turret, a plurality of spindles supported thereon, a retractile pin associated with each of said spindles, means for positioning work pieces on said spindles, resilient means for maintaining said pins normally in position to engage said work pieces, means for rotating said turret, and rockable cam-actuated means for retracting said pins at a predetermined point in their movement with said turret. 15
- 55 17. In a machine of the character described, in combination, a spindle for receiving a work piece, a retractile member for gripping said work piece, said retractile member being slideable longitudinally of said spindle and having a burr at its outer end for engaging said work piece, and rockable cam means for sliding said member relative to said spindle. 20
- 60 18. In a machine of the character described, in combination, a spindle for receiving a work piece, a retractile gripping member associated with said spindle for gripping said work piece, means for maintaining said gripping member normally in engagement with said work piece, and means including a rotatable cam on said spindle for periodically retracting said gripping member. 25
- 65 19. In a machine of the character described, in combination, a frame, an arbor supported on said frame, a turret journaled on said arbor, a plurality of spindles supported thereon, retractile gripping members associated with said spindles, means for normally maintaining said gripping members in advanced position, means for rotating said turret, a rockable member carried by each spindle, and a cam secured to said frame for operating said rockable members and retracting each of said gripping members as it reaches a predetermined position in its movement with said turret. 30
- 70 20. In a machine of the character described, in combination, a spindle, means for presenting a hollow work piece in front of said spindle, and means for pushing said work piece onto said spindle, said means comprising a finger, means for moving said finger outwardly beyond said work piece out of line therewith, means for rocking said finger into alignment with said work piece, and means for moving said finger inwardly to engage said work piece and push it onto said spindle from said presenting means. 35
- 75 21. In a machine of the character described, push-on mechanism comprising an elongated rod, a finger secured upon said rod, means for reciprocating said rod, and friction means for causing rocking of said finger in a vertical plane. 40
- 80 22. In a machine of the character described, push-on mechanism comprising an elongated rod, a finger secured upon said rod, means for reciprocating said rod, and means for rocking said finger upwardly at the beginning of the forward stroke of said rod and downwardly at the beginning of the rearward stroke of said rod. 45

23. In a machine of the character described, push-on mechanism comprising an elongated rod, a finger secured thereon, means for shifting said finger into and out of the path of an article 5 to be engaged, and means for reciprocating said rod, said means including a yoke coupled to said rod and a resilient member adapted to absorb a portion of the back-stroke of said yoke.
24. In a machine of the character described, in 10 combination, a turret, a plurality of spindles journaled therein, means for securing work pieces on said spindles, a thread cutting tool, means for intermittently rotating said turret to index said work pieces successively adjacent said cutting tool, means for bringing said cutting tool into engagement with each successive work piece, means for rotating said spindles and work pieces while adjacent said cutting tool, means for swinging said cutting tool to form a thread on said 15 work piece, and means for retracting said cutting tool.
25. In a machine of the character described, in combination, a turret, a plurality of spindles supported thereon, means for securing work 20 pieces on said spindles, a thread cutting tool, means for intermittently rotating said turret to index said work pieces successively adjacent said thread cutting tool, means for moving said cutting tool bodily into and out of engagement with 25 said work pieces, said last means being arranged to operate in timed relation to said turret-rotating means, and means for swinging said tool while in engagement with the work piece to cut a thread.
26. In a machine of the character described, in combination, a turret, a plurality of spindles supported thereon, means for securing work 30 pieces on said spindles, an elongated cutting tool, means for intermittently rotating said turret to index said work pieces successively adjacent said cutting tool, and means for moving said cutting tool into and out of the path of movement of said spindles and into and out of engagement with 35 said work pieces, said last mentioned means comprising a rock shaft, a lever secured to said rock shaft, a cam roller supported upon said lever, a second lever secured upon said rock shaft, a tool holder carried by said second lever, a cam shaft, a cam secured upon said cam shaft, means for driving said cam shaft, and means for maintaining 40 said cam roller in constant engagement with said cam.
27. In a machine of the character described, in combination, a turret, a plurality of spindles 45 journaled therein, means for securing work pieces on said spindles, a threading tool, means for intermittently rotating said turret to index said work pieces successively adjacent said threading tool, means for moving said threading tool into and out of engagement with said work pieces, means for rotating said spindles and work 50 pieces, means for moving said threading tool longitudinally of said work pieces, and means for independently varying the speed of rotation of 55 said work pieces and the rate of advance of the threading tool.
28. In a machine of the character described, in combination, a turret, a plurality of spindles supported thereon, means for securing work 60 pieces on said spindles, a cutting tool, means for intermittently rotating said turret to index said work pieces successively adjacent said cutting tool, and means for moving said cutting tool into and out of engagement with said work pieces, 65 said last means comprising a lever, a tool holder carried by said lever, said holder being adjustable in three dimensions on said lever, a cam roller supported upon said lever, a cam-shaft, a cam secured upon said cam-shaft, means for driving said cam shaft, and means for maintaining said cam roller in constant engagement with said cam. 70
29. In a machine of the character described, in combination, a turret, a plurality of spindles journaled therein, means for securing work pieces on said spindles, a threading tool, means for intermittently rotating said turret to index said work pieces successively adjacent said threading tool, means for moving said threading tool into and out of engagement with said work pieces, means for rotating said spindles and work 75 pieces, means for moving said threading tool longitudinally of said work pieces at a speed substantially proportional to the speed of rotation of said work pieces, means for jointly varying the speed of operation of said tool moving means and said spindle rotating means, and means for separately varying the speed of said tool moving means.
30. In a machine of the character described, in combination, a turret, a plurality of spindles journaled therein, means for securing work pieces on said spindles, a threading tool, means for intermittently rotating said turret to index said work pieces successively adjacent said threading tool, a holder for said tool, a lever supporting said holder, a lifting lever carrying said first mentioned lever, a cam-shaft, a threading cam and a lifting cam thereon, means for driving said cam-shaft, and means engaging said cams for controlling the operation of said levers. 80
31. In a machine of the character described a rotatable spindle for supporting a work piece, means for rotating said spindle, a threading tool, a pivoted carrier for said tool, means for shifting said carrier bodily to bring the tool into engagement with the work piece, and means for rocking the carrier to move the tool along the work piece. 85
32. In a machine of the character described a rotatable spindle for supporting a work piece, means for rotating said spindle, a threading tool, a pivoted carrier for said tool, said carrier being arranged to swing said tool from a position adjacent the end of said work piece inwardly thereof, means for shifting said carrier to bring the tool into engagement with the work piece, and means for rocking the carrier to move the tool along the work piece, the low point of the arc being adjacent the end of the work piece. 90
33. In a machine of the character described a rotatable spindle for supporting a hollow work piece, means for rotating said spindle, a threading tool, means for moving said tool into and out of engagement with the work piece, means for advancing the tool along the work piece, common operating means for rotating said spindle and shifting said tool, and means adjustable at will for varying the rate of advance of said tool along the work piece relative to the rotation of said spindle. 95
34. In a machine of the character described, in combination, a turret, a plurality of spindles supported thereon, means for positioning work pieces upon said spindles, capping mechanism including a rockable and bodily slidably arm, means on said arm for carrying a cap, and means for rotating said turret to present said work pieces successively to said capping mechanism. 100
35. In a machine of the character described, in combination, a turret, a plurality of spindles 75

- supported thereon, means for positioning work pieces upon said spindles, capping mechanism including a chuck carried by a rock arm, means for rocking said arm to carry said chuck from a 5 cap receiving to a cap applying station, means for intermittently rotating said turret to present said work pieces successively to said applying station, and means for producing a cap applying movement between said chuck and the spindles at said 10 station.
36. In a machine of the character described, in combination, a turret, a plurality of spindles journaled therein, means for securing work pieces upon said spindles, a rock arm, a cap retaining chuck carried by said arm, means for rocking said arm to carry the chuck from a cap receiving to a cap applying station, means for intermittently rotating said turret to present said spindles successively to said cap applying station, 15 means for producing a cap applying movement between said chuck and the spindles at said station and means for rotating each of said spindles and its associated work piece while at said cap applying station.
37. In a machine of the character described, in combination, capping mechanism arranged at a capping station means for presenting a threaded work piece at said capping station, and means for rotating said work piece relative to a cap 20 while at said station, said capping mechanism comprising means for feeding a supply of screw caps, means for inserting gaskets into said caps, and means for bringing a screw cap into engagement with said threaded work piece during 25 said relative rotation at said capping station.
38. In a machine of the character described, in combination, capping mechanism arranged at a capping station, means for presenting a threaded work piece at said capping station, and means 30 for rotating said work piece relative to a cap while at said station, said capping mechanism comprising means for feeding a supply of screw caps, means for forming gaskets, means for inserting said gaskets in said cap, and means for 35 bringing a screw cap into engagement with said threaded work piece during said relative rotation at said capping station.
39. In a machine of the character described, in combination, capping mechanism arranged at a capping station, means for presenting a threaded work piece at said capping station, and means 40 for rotating said work piece relative to a cap while at said station, said capping mechanism comprising means for feeding a supply of screw caps, means for forming gaskets, means for inserting said gaskets in said cap, and means for 45 bringing a screw cap into engagement with said threaded work piece during said relative rotation at said capping station.
40. In a machine of the character described, in combination, capping mechanism arranged at a capping station, means for presenting a threaded work piece at said capping station, and means 50 for rotating said work piece relative to a cap while at said station, said capping mechanism comprising means for feeding a supply of screw caps, means for feeding a strip of gasket material, means for forming gaskets therefrom, means for inserting said gaskets in said caps, and means for bringing 55 one of said caps into engagement with each of said threaded work pieces while at said capping station.
41. In a machine of the character described, capping mechanism comprising means for feeding a supply of screw caps, means for feeding a strip of gasket material, means for forming gaskets from said strip of material, means for inserting said gaskets in said screw caps, and means for disposing of the scrap resulting from 60 said gasket forming operation.
42. In a machine of the character described, in combination, a turret, a plurality of spindles 65 journaled in said turret, means for securing threaded work pieces on said spindles, means for rotating said turret to present said spindles and work pieces successively at a capping station, capping mechanism at said station, and means for rotating said spindles and said work pieces relative to a cap while at said station, said capping mechanism comprising means for feeding a supply of screw caps, means for inserting gaskets in said caps, and means for bringing one of said caps into engagement with each of 70 said threaded work pieces while at said capping station.
43. In a machine of the character described, in combination, a turret, a plurality of spindles journaled in said turret, means for securing threaded work pieces on said spindles, means for rotating said turret to present said spindles and work pieces successively at a capping station, capping mechanism at said station, and means for rotating said spindles and said work pieces relative to a cap while at said station, said capping mechanism comprising means for feeding a supply of screw caps, means for forming gaskets, means for inserting said gaskets in said caps, and means for bringing one of said caps into engagement with each of said threaded work pieces while at said capping station.
44. In a machine of the character described, in combination, a turret, a plurality of spindles journaled in said turret, means for securing threaded work pieces on said spindles, means for rotating said turret to present said spindles and work pieces successively at a capping station, capping mechanism at said station, and means for rotating said spindles and said work pieces relative to a cap while at said station, said capping mechanism comprising means for feeding a supply of screw caps, means for feeding a strip of gasket material, means for forming gaskets therefrom, means for inserting said gaskets in said caps, and means for bringing one of said caps into engagement with each of said threaded work pieces while at said capping station.
45. In a machine of the character described, in combination, a turret, a plurality of spindles journaled in said turret, means for securing threaded work pieces on said spindles, means for rotating said turret to present said spindles and work pieces successively at a capping station, capping mechanism at said station, and means for rotating said spindles and said work pieces relative to a cap while at said station, said capping mechanism comprising means for feeding a supply of screw caps, means for feeding a strip of gasket material, means for forming gaskets therefrom, means for inserting said gaskets in said caps, means for disposing of the scrap resulting from said gasket-forming operation, and means for bringing one of said caps into engagement with each of said threaded work pieces while at said capping station.
46. In a machine of the character described, in combination, a turret, a plurality of spindles

supported thereon means for securing work pieces on said spindles, means for threading said work pieces, means for presenting said work pieces successively at a capping station, means for feeding a supply of screw caps, means for inserting gaskets in said caps, and means for threading one of said caps onto each of said work pieces while at said capping station.

47. In a machine of the character described, in combination, a turret, a plurality of spindles journaled therein, means for securing work pieces on said spindles, means for presenting said spindles and work pieces successively at a threading station, means for rotating said spindles and work pieces at a predetermined speed while at said threading station, a threading tool at said threading station, means for bringing said threading tool into engagement with each of said work pieces while rotating at said station, means for presenting said spindles and work pieces successively at a capping station, means for rotating said spindles and work pieces at said capping station at a speed different from the speed of rotation at said threading station, means for feeding a supply of screw caps, and means for bringing one of said caps into engagement with each of said work pieces while rotating at said capping station.

48. In a machine of the character described, a capping mechanism comprising a rock shaft, a lever secured thereto, a chuck carried by said lever, means for rocking said chuck to cap-receiving position, means for positioning a cap in said chuck, means for rocking said chuck to cap-applying position, and means for moving said chuck bodily to apply and release said cap.

49. In a machine of the character described, a capping mechanism comprising means for feeding caps, means for feeding gasket material, means for forming gaskets from said material, a chuck, and single means for inserting said gaskets into said caps and positioning said caps in said chuck.

50. In a machine of the character described, a capping chuck comprising a plunger, means carried by said plunger and adapted to receive and grip a cap, and a push rod slidably mounted in said plunger and normally held stationary relative to said plunger by friction.

51. In a machine of the character described, in combination, a capping chuck comprising a plunger, means carried by said plunger and adapted to receive and grip a cap, and a push rod slidably mounted in said plunger and normally held stationary relative to said plunger by friction, and means for moving said push rod forwardly in said plunger before each insertion of a cap in said chuck.

52. In a machine of the character described, in combination, a capping chuck comprising a plunger, means carried by said plunger and adapted to receive and grip a cap, and a push rod slidably mounted in said plunger and normally held stationary relative to said plunger by friction, and means whereby said push rod is moved forwardly in advance of each insertion of a cap and is moved rearwardly upon such insertion.

53. In a machine of the character described, a capping chuck comprising a plunger, means carried by said plunger for receiving and gripping a cap, and separate yielding means for resisting the insertion of a cap in said chuck and providing support for the head thereof.

75 54. In a machine of the character described, a

capping chuck comprising a plunger, means carried by said plunger for receiving and gripping a cap, and separate yielding means for resisting the insertion of a cap in said chuck, said separate means being provided with a flat forward surface of approximately the size and shape of the head of the cap to be received.

55. In a machine of the character described a capping chuck comprising a plurality of spring urged jaws, means for forcing a cap into said jaws, and means for maintaining the cap in proper alignment as it is forced into the jaws.

56. In a machine of the character described, means for feeding a strip of gasket material, means for forming gaskets therefrom, means for severing the remaining gasket scrap into relatively small pieces, a scrap chute and means for conveying said scrap to said chute.

57. In a machine of the character described, means for feeding a strip of gasket material, a gasket die, a gasket punch, a scrap die, a scrap punch, means for forcing said punches into said dies, and means for supplying a jet of air adjacent said scrap punch.

58. In a machine of the character described, a capping mechanism comprising means for providing a supply of caps, means for feeding a strip of gasket material, a gasket die, a reciprocative gasket punch, a reciprocative pusher rod slidably mounted within said punch, a capping chuck, means for moving said punch forwardly to form a gasket, means for moving said pusher rod forward to insert said gasket in a cap and to push said cap into said chuck, and means for retracting said punch and said pusher rod.

59. In a machine of the character described, in combination, a spindle, means for positioning a work piece on said spindle, means for trimming said work piece while on said spindle, and means for sliding the scrap to remove it from said spindle.

60. In a machine of the character described, in combination, a spindle, means for positioning a work piece on said spindle, means for trimming said work piece while on said spindle, and means for removing the scrap from said spindle, said last means comprising a finger, means for moving said finger to engage said scrap and strip it from said spindle, and means for retracting said finger.

61. In a machine of the character described, in combination, a turret, a plurality of spindles supported thereon, means for positioning work pieces on said spindles, means for rotating said turret to present each of said work pieces successively at a trimming station and a scrap removal station, means at said trimming station for trimming said work pieces, and means at said scrap removal station for sliding the scrap to remove it from said spindles.

62. In a machine of the character described, a scrap removal mechanism comprising a reciprocative rod, a finger carried by said rod, means for reciprocating said rod, means for rocking said finger on said rod at the beginning of the rearward stroke of said rod, and means for restoring said finger to normal position relative to the rod at the end of said rearward stroke.

63. A combination machine for finishing collapsible metal tubes, comprising a turret, spindles journaled in said turret, a motor, means connecting said motor and said turret, means connecting said motor and said spindles, a plurality of tool-operating mechanisms, a push-on mechanism, a capping mechanism, a scrap-removal mechanism, and means connecting said motor

and said mechanisms for operating said mechanisms in timed relation to each other and to the movements of said turret.

64. In a machine of the character described 5
 5 a rotatable head, a plurality of work receiving spindles on said head, means for rotating said turret to carry said spindles to successive stations, means at the several stations for performing a number of successive operations on the work carried by said spindles, and means for rotating the spindles at different speeds at different stations, said last mentioned means including a plurality of belts, at least one of said belts driving said spindles continuously while they are in a zone 10
 10 occupied by a plurality of stations.

65. In a machine of the character described a rotatable head, a plurality of work receiving spindles on said head, means for rotating said turret to carry said spindles to successive stations, means at the several stations for performing a number of successive operations on the work carried by said spindles, means for rotating the spindles at different speeds at different stations, and means for jointly varying the speed of rotation of said spindles at a plurality of said stations 15 independently of other stations.

66. In a machine of the character described a rotatable head, a plurality of work receiving spindles on said head, means for rotating said 20 turret to carry said spindles to successive stations, means at one of said stations for applying a coating to the work, means at another of said stations for applying a cap to a threaded portion of the work, and means for rotating the spindles at 25 different speeds at said stations.

67. In a machine of the character described a rotatable head, a plurality of work receiving spindles on said head, means for rotating said turret to carry said spindles to successive stations, means at one of said stations for applying a coating to the work, means at another of said stations for applying a cap to a threaded portion of the work, means for rotating the spindles at different 30 speeds at said stations and means for varying the speed of rotation of the spindle at one of said stations independently of the other.

68. In a machine of the character described a

rotatable head, a plurality of work receiving spindles on said head, means for rotating said turret to carry said spindles to successive stations, means at one of said stations for threading the end of the work, means at another of said stations for applying a coating to the work, means, at a third one of said stations for applying a cap to the threaded end of the work and means for rotating said turret and for rotating the spindles at the several stations.

69. In a machine of the character described a rotatable head, a plurality of work receiving spindles on said head, means for rotating said turret to carry said spindles to successive stations, means at one of said stations for threading 15 the end of the work, means at another of said stations for applying a coating to the work, means at a third one of said stations for applying a cap to the threaded end of the work, means for rotating said turret and for rotating the spindles 20 at the several stations, and means for varying the speed of rotation of the spindles at one station independently of another.

70. In a machine of the character described a rotatable head, a plurality of work receiving 25 spindles on said head, means for rotating said turret to carry said spindles to successive stations, means at one of said stations for applying a coating to the work, means at another of said stations for applying a cap to a threaded portion 30 of the work, means for rotating the turret and for driving the spindle at one of said stations, and separate means for driving the spindle at the other of said stations.

71. In a machine of the character described a rotatable head, a plurality of work receiving spindles on said head, means for rotating said turret to carry said spindles to successive stations, means at one of said stations for applying a coating to the work, means at another of said 35 stations for applying a cap to a threaded portion of the work, means deriving power from one source for rotating the turret and for driving the spindle at one of said stations, and separate means deriving power from another source for 40 driving the spindle at the other of said stations.

JOHN H. FRIDÉN.
